(57) **CLAIM**

The ornamental design for a control panel for a road construction machine, as shown and described.

DESCRIPTION

FIG. 1 front side view of the design for a control panel for a road construction machine of the present invention.

FIG. 2 is a right side view of the design for control panel for a road construction machine of FIG. 1.

FIG. 3 is a rear side view of the design for a control panel for road a construction machine of FIG. 1.

FIG. 4 is a left side view of the design for a control panel for a road construction machine of FIG. 1.

FIG. 5 is a top side view of the design for a control panel for a road construction machine of FIG. 1.

FIG. 6 is a bottom side view of the design for a control panel for a road construction machine of FIG. 1.

FIG. 7 is a perspective view onto the front side, right side and top side of the design for a control panel for a road construction machine of FIG. 1;

FIG. 8 is a further perspective view onto the rear side, left side and top side of the design for a control panel for a road construction machine of FIG. 1.

FIG. 9 is a front side view of a second embodiment of the design for a control panel for a road construction machine in the present invention.

FIG. 10 is a right side view of the design for a control panel for a road construction machine of FIG. 9.

FIG. 11 is a rear side view of the design for a control panel for a road construction machine of FIG. 9.

FIG. 12 is a left side view of the design for a control panel for a road construction machine of FIG. 9.

FIG. 13 is a top side view of the design for a control panel for a road construction machine of FIG. 9.

FIG. 14 is a bottom side view of the design for a control panel for a road construction machine of FIG. 9.

FIG. 15 is a perspective view onto the front side, right side and top side of the design for a control panel for a road construction machine of FIG. 9; and,

FIG. 16 shows a further perspective view onto the rear side, left side and top side of the design for a control panel for a road construction machine of FIG. 9.

1 Claim, 16 Drawing Sheets
